UNITED STATES PATENT OFFICE.

THOMAS E. LEWIS, OF VICKSBURG, MISSISSIPPI, ASSIGNOR OF TWO-THIRDS
TO THOMAS MACKENZIE AND WILLIAM T. HOWARD, OF BALTIMORE,
MARYLAND.

SHOE-LACE.

SPECIFICATION forming part of Letters Patent No. 667,025, dated January 29, 1901.

Application filed January 30, 1900. Serial No. 3,276. (No model.)

To all whom it may concern:

Be it known that I, THOMAS E. LEWIS, of the city of Vicksburg, in the county of Warren and State of Mississippi, have invented 5 certain Improvements in Shoe-Laces, of which the following is a specification.

The object of this invention is to construct a shoe-lace in such manner that it will hold a shoe in a laced condition without its being 10 tied and without the employment of any devices to coöperate with it other than the eyelets and hooks commonly used.

The said invention, briefly stated, consists in distending a tubular shoe-lace subsequent 15 to the lacing operation from its ends to points where it comes into contact with the upper hooks or any hooks below them, which may be selected by means of the metallic tags which are pushed down into the lace, the tags 20 being prevented from returning by upturned spurs formed on the tags adapted to engage with and catch the upper surface of the lace. By this operation the lace is thickened from the hooks upward, so as to preclude their passing 25 through the hooks, and the shoe is held in a laced condition fully as well as if the lace were tied.

In the further description of the said invention which follows reference is made to 30 the accompanying drawings, forming a part hereof, and in which—

Figure 1 is a perspective view of a shoe laced in accordance with the present invention. Fig. 2 is a view of one end of the lace 35 having an ordinary tag provided with spurs adapted to be turned upward or toward the body of the tag. Fig. 3 is an edge view of Fig. 2. Fig. 4 is a view similar to Fig. 3 except that the spurs of the tag are turned up 40 after the manner of the arms of an anchor. Fig. 5 illustrates the relative positions of the lace and its tag at the beginning of the invention of the tubular lace. Fig. 6 is a sectional view of the lace, showing the tag wholly 45 within it and anchored by means of the bent-up spurs. Fig. 7 is an outside view of Fig. 6.

Referring now to the drawings, A represents a shoe, and B the shoe-lace, which in Fig. 1 is shown as passed through the eyelets 50 a and over the hooks b.

Supposing the shoe to be on the foot and the lace threaded through the eyelets, the manner of completing the lacing is as follows: The ends of the lace are drawn tightly and passed over the hooks b or as many of them 55 as is necessary or desired and again drawn until the proper tension is secured. The spurs are then turned up and the butt of each tag pushed into the lace and worked down until the thickened portion effected by the 60 presence of the tag comes against the top hook or the last of the series used, the upwardly-turned spurs preventing the return of the tag. The fastening is then complete.

It will be understood that the portion of 65 the lace above the hooks is enlarged or distended by the tag and an extra thickness of lace, and the enlargement will not pass through the hook, while it does not interfere with the disengagement of the lace from the 70 top hooks when the lace is to be slackened as a preliminary measure to the removal of the shoe from the foot.

The lacing can at any time be tightened by 75 sliding the spurred tags farther down the lace, the tags being held after such movement by the spurs.

The addition of the spurs to the tags does not appreciably increase their cost. Neither do the spurs interfere with the tying of the 80 lace should that mode of securing it be desired.

I claim as my invention—

1. In combination with a tubular shoe-lace, a tag secured thereto having spurs which are 85 adapted to be upturned or made to fall back toward the body of the tag, substantially as, and for the purpose specified.

2. In combination with a tubular shoe-lace, an attached tag having a spur projecting from 90 the same and extending over the lace, said spur being adapted to be turned upward or toward the body of the tag, substantially as specified.

THOMAS E. LEWIS.
